UNITED STATES PATENT OFFICE.

WILLIAM NICHOLS, OF KANSAS CITY, KANSAS.

TRAIN-ORDER SIGNAL-BOARD.

SPECIFICATION forming part of Letters Patent No. 634,268, dated October 3, 1899.

Application filed May 13, 1899. Serial No. 716,754. (No model.)

To all whom it may concern:

Be it known that I, WILLIAM NICHOLS, a citizen of the United States, residing at Kansas City, in the county of Wyandotte and 5 State of Kansas, have invented a new and useful Improvement in Train-Order Signal-Boards, of which the following is a specification.

My invention relates to train-order signal-10 boards, and my primary object is to produce a device of this character which will safeguard the mind of the telegraph-operator by making it impossible for him to copy a train-order with the official stylus until the danger-sig-15 nal—viz., the red signal—is properly displayed and which prevents the signal being locked “clear” or “white” (signifying “all right” or “no orders”) by any instrument other than the official stylus or its duplicate, 20 thereby insuring that the stylus is always in position and ready for action when the signal is “clear” or by its absence that the danger-signal is displayed.

To these ends the invention consists in cer-25 tain novel and peculiar features of construction and combinations of parts, as hereinafter described and claimed, and in order that it may be fully understood reference is to be had to the accompanying drawings, in which—

30 Figure 1 represents a top plan view of a train-order signal-board mechanism embodying my invention. Fig. 2 is an enlarged view of the same, partly in section. Figs. 3, 3^a, and 3^b represent enlarged sectional views, 35 Figs. 3 and 3^a being taken on dotted lines III and III^a III^b, respectively, of Fig. 1 and Fig. 3^b on the dotted line III^b III^b of Fig. 2. Fig. 4 is a detail perspective view of the inner stationary guard-plate. Fig. 5 is a similar view of the inner movable guard-plate. Fig. 6 is a similar view of the outer station-40 ary guard-plate. Fig. 7 is a similar view of the outer movable guard-plate. Fig. 8 is a detail view, partly in section and partly in 45 elevation, of the outer stationary guard-plate to show clearly the opening thereof. Fig. 9 is a detail side view of the upper end of the signal proper.

Referring to the drawings in detail, 1 des-50 ignates an approximately semicircular board adapted to be secured in a horizontal position

adjacent to the operator’s desk or table in order that the operator may without the slightest inconvenience reach the same.

2 designates the inner stationary guard-55 plate, secured to the curved periphery of the board and provided with an opening 3, communicating with a small radial opening 1^a of the board, said opening being designed to receive the writing-point of the stylus, as here- 60 inafter explained.

4 designates the outer stationary guard-plate, extending parallel with the guard-plate 2 and secured thereto and to the board, as shown, or in any other suitable or preferred 65 manner, said outer stationary guard-plate at a point in radial alinement with the opening 3 being provided with a corresponding opening 5, which opening also extends or continues through the enlargement or boss 6, formed ex- 70 ternally of or secured to the plate 4, the opening or passage 5 being provided with the inwardly-projecting lugs 7.

8 designates a bolt which extends vertically 75 through the board centrally of said curved guard-plate, and 9 a bell-crank lever mounted pivotally on said bolt and connected by a link-rod 10 or its equivalent to the arm 11 of the signal mechanism located at the proper point alongside the track, (not shown,) the 80 usual red or danger signal 12 being moved parallel with or at right angles to the track accordingly as the arm 11 is thrown to the position shown in full or in dotted lines, Fig. 1, it being understood that the customary spring 85 (not shown) or its equivalent is relied on to throw the signal to the danger position, as shown in dotted lines, when the telegraph operator removes his stylus from the board, though it is to be further understood and 90 hereinafter appears that in case the spring fails to work the operator will be compelled to operate the signal by hand (without leaving his seat) before he can remove the stylus to copy the train-order.

Extending concentrically of the lever-axis 95 and secured to the board in any suitable manner is a friction-bar 13, and bearing upon the same is a spring-arm 14, projecting outward from the lever and formed with or carrying 100 at its outer end an inverted-U-shaped bracket 15, one arm of which depends into the space

between the stationary guard-plates. A similar bracket 16, secured to the opposite end of the lever, has one of its arms depending into the space between said stationary guard-plates, and connecting these brackets are the parallel movable guard-plates, the inner one, located between guard-plates 2 and 4, being numbered 17 and the outer one 18. The inner movable guard-plate is provided with a longitudinal slot 19, which terminates in an enlargement or opening 20, corresponding in form and size to the openings 3 and 5 of the stationary guard-plates. The outer movable guard-plate is provided with a similar longitudinal slot 21 and terminates at its rear end in an enlargement or opening 22, which opening corresponds in size and form to the openings 3, 5, and 20, and said openings are by preference of triangular form for a reason which is hereinafter explained.

By the construction just described it is apparent that when the lever is in the position shown in full lines, Fig. 1, and the signal, consequently, is clear the movable guard-plates are disposed with the front ends of their slots registering with the openings 3 and 5—that is to say, the enlargement or opening 20 of the inner movable guard-plate registers with the openings 3 and 5 and the opening 1^a of the board, but the enlargement or opening of the outer movable guard-plate does not. The effect of this arrangement on the stylus is hereinafter explained.

In order to act as a guide for the lever 9 and positively arrest it at the proper limit of its travel in either direction, a guide-slot is formed by means of the curved plates 23 and 24, secured in a parallel relation to the face of the board 1, the plate 24 being secured to the upturned ends of the plate 23, with the lever extending through the slot, as shown.

Near its front end the plate 23 is provided with an opening 25, communicating with the recess 26 in the face of the board, and bolted or otherwise secured in said recess is a spring-catch 27, normally projecting up through the opening 25 in the path of the lever and provided at its free end with a finger-piece 28, whereby the catch may be depressed by hand out of the path of the lever.

In order that this signal-board may be a necessary or desirable adjunct to a telegraph-operator's office, it is essential that the company prescribe an official stylus for use in copying train-orders, which stylus when out of service—that is, after all orders have been copied and delivered—must be secured to the train-order signal-board in such manner that it cannot be removed therefrom unless the signal occupies its danger position, and in order to prevent the operator from locking the signal-board "clear" with a nail, lead-pencil, or other convenient object the opening or openings to receive the stylus are of peculiar configuration, so that by the stylus alone or its duplicate can the signal-board be locked "clear." This obviously insures that

the stylus is always in its proper position and the signal ready for action when it is necessary for the operator to copy a train-order. 70

Referring now to the construction of the stylus, it consists of a stem or handle portion 29, sufficiently small at its lower end to pass through the slot 21 of the outer movable guard-plate, the enlargement 30 corresponding in form to but being slightly smaller than the openings 3 6 20 22 and provided with grooves 31 to receive the lugs 7 hereinbefore described (see Fig. 8) and the stylus-point 32 to enter the recess 1^a of the board, said point 80 being sufficiently small to pass through the slot 19 of the inner movable guard-plate.

In practice, assuming that the signal-board is locked "clear," it will be seen by reference to Fig. 2 that the enlargement 30 of the stylus extends through the registering openings 5 20 3 and that the writing-point occupies the recess 1^a of the board. It will also be noticed that the stem or handle at a point where it is smaller than the enlargement extends through the slot 21 of the outer movable guard-plate and that owing to the fact that the enlargement 30 extends through the opening or enlargement 20 of the inner movable guard-plate the signal is locked "clear." Supposing now that the operator is to make a copy of a train-order, he reaches up and pulls the stylus outward until the enlargement is withdrawn entirely through the opening 20 of the inner movable guard-plate and about the same instant strikes against the inner side of the outer guard-plate, because it cannot pass through the narrow slot 21. This movement of the stylus is instantly followed by the automatic operation of the signal by the spring thereof, and the movement of the signal of course imparts a corresponding movement to the signal-board mechanism—that is to say, the lever and movable guard-plates carried thereby swing from the position shown in full lines, Fig. 1, to the position shown in dotted lines, the lever in this action depressing the spring-catch, which at the termination of the lever movement springs up to its normal position and, locking the lever, locks the signal in its danger position. At the termination of the lever movement the opening or enlargement 22 of the movable guard-plate 18 registers with the opening 5 and permits the withdrawal of the stylus by the operator, who then makes his copy of the order and after delivering all orders reinserts the stylus, which, however, cannot be forced inward to its original position, because the inner end of the enlargement bears against the outer side 125 of the inner movable guard-plate at the rear end of slot 19, the writing-point projecting through said slot in an obvious manner. If the operator fails to return the signal to the clear position after the train has passed, for which a copy of said order was intended, the danger-signal will remain displayed and will cause the next train to stop. To avoid this unnecessary delay, the operator should trip

135

the spring-catch 27 by depressing its finger-piece 28 and throw the signal to "clear" by returning the lever to the position shown in full lines, Fig. 1, and as this movement is effected he must lock the signal in its clear position by pushing the stylus inward until its enlargement 30 enters the opening or enlargement 20 of the inner movable guard-plate, which opening at this time again registers 5 with the openings 2 and 5. By the same movement which caused this opening to re-register and permit the signal to be locked "clear" by the inward movement of the stylus, the latter was also locked against removal 10 until the opening or enlargement 22 again registers with the opening 5.

It was found in practice the slot of the inner movable guard-plate could be dispensed with, though at the risk of breaking the point 20 of the stylus, because the action of the signal-spring is so quick that it would cause the abrupt wall of the opening of said plate to strike against the point before the latter could be completely withdrawn through said opening. 25 With this communicating slot as soon as the enlargement 30 is withdrawn the signal is thrown without bringing any pressure to bear upon the stylus-point at all, because the slot is sufficiently large to play loosely 30 upon said point. Furthermore, without said slot a nail or piece of wire small enough to pass between the lugs 7 could be inserted to lock the signal "clear;" but with it, as the width of the slot is equal to the diameter 35 of the space between said lugs, this object cannot be accomplished, and it is necessary in order to lock the signal "clear" that the official stylus or its exact duplicate be employed. It would be against the orders of the 40 company, of course, for an operator to provide himself with such duplicate, so as to insure that the signal-board is in proper working position at all times and therefore an absolutely reliable safeguard to the mind of the 45 despatcher. Furthermore, it will be difficult, or at least inconvenient, for a despatcher to obtain a duplicate of this stylus, because the company can control the source of supply. While the cross-sectional configuration of the 50 stylus and of the openings made to receive it is of no especial importance as regards the operation of the "board," such configuration is preferred, because it is more convenient and comfortable to the grasp of the despatcher, 55 while writing and because in that form it can be reduced to a minimum weight, this reduction in weight being an object, because it will probably be necessary to make the stylus of metal, preferably aluminium, because a heavier metal would soon tire the 60 hand of the operator. It will be apparent also that the plate 2, termed the "inner stationary guard-plate," may be dispensed with if the part 1 should be constructed of metal, 65 as the main function of said plate is to provide a wear-surface for the part 1, though of course there must be an opening or recess 3

to receive the inner end of the enlargement of the stylus to lock the signal-board "clear."

From the above description it will be apparent that I have produced a train-order signal-board which embodies the features of advantage enumerated in the statement of invention and which, furthermore, is of exceedingly simple, compact, durable, and inexpensive construction. 70

It is to be understood, of course, that the board may be used vertically instead of horizontally and that the special construction of the signal mechanism or of its connection 80 with the signal-board is material only to the extent that the operation of one shall impart a corresponding movement to the other. It is also to be understood that various changes in the detail construction, form, arrangement, or proportion of the parts may be made 85 without departing from the essential spirit and scope or sacrificing any of the advantages of my invention.

Having thus described the invention, what 90 I claim as new, and desire to secure by Letters Patent, is—

1. In a train-order signal-board, a stationary guard-plate, a movable guard-plate arranged and adapted to move in a plane substantially parallel with the stationary guard-plate, a signal operatively connected to said movable guard-plate, and a stylus adapted to lock said guard-plates together when the signal is "clear," substantially as described. 95

2. In a train-order signal-board, a stationary guard-plate having an opening, a movable guard-plate having an opening, a signal operatively connected to said movable guard-plate, and a stylus removably engaging the 100 openings of said guard-plates when the danger-signal is set, substantially as described.

3. In a train-order signal-board, a guard-plate having an opening, a movable guard-plate having an opening, one of said guard-plates also having a slot narrower in width 105 than and communicating at one end with its opening, and a stylus projecting through the slotted guard-plate and engaging the opening of the other guard-plate, substantially as 110 described.

4. In a train-order signal-board, a stationary guard-plate having an opening, a movable guard-plate having a slot terminating in an enlargement or opening, a signal operatively 115 connected to the movable guard-plate, and a stylus with its stem or handle small enough to pass through said slot and provided with an enlargement fitting in the opening of the stationary guard-plate and adapted to be withdrawn through the opening or enlargement of the movable plate when the danger-signal is set, substantially as described. 120

5. In a train-order signal-board, a stationary guard-plate having an opening, an inner 130 and an outer movable guard-plate at opposite sides of the stationary plate, the inner one having an opening and the outer one a slot terminating in an enlargement or opening, a

signal operatively connected to said movable guard-plates, and a stylus with its stem extending through the slot of said outer guard-plate and provided with an enlargement engaging the registering openings of the stationary and inner movable guard-plates and locking the signal "clear," substantially as described.

6. In a train-order signal-board, a stationary guard-plate having an opening, slotted inner and outer movable guard-plates at opposite sides of the stationary plate, the slot of the inner plate terminating at its front end in an enlargement or opening and the slot of the outer plate in an enlargement or opening at its rear end, a signal operatively connected to said movable guard-plates, and a stylus having its enlargement fitting in the opening of the stationary guard-plate when the danger-signal is set, its stem or handle projecting outward through the registering enlargement or opening of the outer movable guard-plate, and its writing-point projecting inward through the slot of the inner movable guard-plate, substantially as described.

7. In a train-order signal-board, a stationary guard-plate, having an opening, a movable guard-plate having a slot terminating in an enlargement or opening, a signal operatively connected to the movable plate, a stylus with its stem or handle small enough to pass through said slot and provided with an enlargement fitting in the opening of the stationary guard-plate and adapted to be with-

drawn through the enlargement or opening 35 of the movable plate when the danger-signal is set, and means to lock said plates together when said openings register, substantially as described.

8. In a train-order signal-board, a stationary guard-plate having an opening, and lugs projecting inward thereof, a movable guard-plate having a slot terminating in an enlargement or opening, a signal, and a stylus with its stem or handle small enough to pass 45 through said slot and provided with an enlargement fitting in the opening of the stationary guard-plate and provided with grooves to receive said lugs, substantially as described.

9. In a train-order signal-board, a stationary guard-plate having an opening, a movable guard-plate having a slot terminating in an enlargement or opening, a signal, a lever connected to the signal and carrying said movable guard-plate, a stylus with its stem or 55 handle small enough to pass through said slot and provided with an enlargement fitting in the opening of the stationary guard-plate, a friction-bar to prevent accidental movement of the lever, and a spring-catch to engage the lever when the danger-signal is set, substantially as described.

In testimony whereof I affix my signature in the presence of two witnesses.

WILLIAM NICHOLS.
